DESIGN.

No. 35,281.

Patented Nov. 12, 1901.

J. W. BRAYMAN.

MUSTACHE GUARD.

(Application filed Sept. 28, 1901.)

WITNESSES

M. M. Martin
F. T. Brown,

INVENTOR
J. W. Brayman
by C. H. Gates, Attorney

UNITED STATES PATENT OFFICE.

JOHN W. BRAYMAN, OF SILVERSPRINGS, NEW YORK.

DESIGN FOR A MUSTACHE-GUARD.

SPECIFICATION forming part of Design No. 35,281, dated November 12, 1901.

Application filed September 28, 1901. Serial No. 76,961. Term of patent 3½ years.

To all whom it may concern:

Be it known that I, JOHN W. BRAYMAN, a citizen of the United States, residing at Silversprings, in the county of Wyoming and State of New York, have invented and produced a new and original Design for a Mustache-Guard; and I do declare the following to be a full, clear, and exact description of the same, reference being had to the accompanying drawings, forming a part thereof.

My invention relates to a novel design for a mustache-guard; and it consists in the novel contour, all as will be hereinafter fully described, and pointed out in the appended claim.

The annexed drawings, to which reference is made, fully illustrate my new design, in which—

Figure 1 represents a perspective view of my device. Fig. 2 is a plan view. Fig. 3 is an edge view, and Fig. 4 is a vertical transverse sectional view.

As shown in the drawings, the leading feature of my design consists of a pair of lateral extensions a a, that are connected or joined to one another by a horizontal plate, forming the body of the guard. These extensions or twin wings a a curve from the horizontal flat portion c c downward, where they meet the intermediate flat plate at the point d d, while the two opposite ends thereof curve outward from the point e to the point f to the straight edge g, when the edge of the plate curves inward, presenting an arc of a circle, as shown at h.

The edge of the guard, as at i, presents a straight line when viewed from above, and projecting from the depressed portion of the guard is a bar bent in the shape of a hook, as shown at j.

Having thus described my invention, what I claim as new, and desire to secure by Letters Patent, is—

The design for a mustache-guard, as herein shown and described.

JOHN W. BRAYMAN.

Witnesses:

R. B. BRAYMAN,
C. D. EASTMAN.